UNITED STATES PATENT OFFICE

164,142

ELECTRIC RANGE BACKSPLASHER

Thomas M. Steinbach, Chicago, Ill., assignor to
Hotpoint Inc., a corporation of New York

Application April 25, 1951, Serial No. 14,946

Term of patent 14 years

(Cl. D81—25)

To all whom it may concern:

Be it known that I, Thomas M. Steinbach, a citizen of the United States, residing at Chicago, State of Illinois, have invented a new, original, and ornamental Design for Electric Range Back-splasher, of which the following is a specification, reference being had to the accompanying drawing, forming a part hereof.

Fig. 1 is a front elevation of an electric range backsplasher embodying my new design.

Fig. 2 is a side sectional elevation thereof looking in the direction of the arrows 2—2 of Fig. 1.

Fig. 3 is a side sectional elevation thereof taken on lines 3—3 of Fig. 1.

Fig. 4 is a side sectional elevation thereof looking in the direction of the arrows 4—4 of Fig. 1.

I claim:
The ornamental design for an electric range backsplasher, as shown.

THOMAS M. STEINBACH.
